HIS ATTORNEY'S.

UNITED STATES PATENT OFFICE.

WILLIAM TRIPPE, OF HOLSTEIN, MISSOURI.

CLAMPING-TOOL.

1,265,141.

Specification of Letters Patent.

Patented May 7, 1918.

Application filed December 24, 1917. Serial No. 208,540.

To all whom it may concern:

Be it known that I, WILLIAM TRIPPE, a citizen of the United States, residing at Holstein, county of Warren, and State of Missouri, have invented a new and useful Clamping-Tool, of which the following is a specification.

This invention relates to clamping tools.

In boring wells and the like a part of the 10 boring mechanism or tube sometimes becomes detached from the operating mechanism which is above the ground so that it is often exceedingly difficult and frequently impossible to withdraw or remove the detached part from the well or the like. Devices have been provided for the purpose of 15 engaging and withdrawing the detached part from the well but such devices have been unsuccessful to a large extent, for the reason that it is difficult and in many instances impossible to engage such devices with the detached parts in the well with sufficient firmness or rigidity to hold and withdraw the detached part from the well. 20 Moreover, the devices now in use for such purposes are cumbersome and expensive and too easily damaged.

The object of my present invention is to provide an improved clamping tool to serve 30 the purposes mentioned and which is not subject to the objections stated; so that when the device is lowered into the well it will with certainty effect firm and rigid engagement with the detached part of the boring mechanism or machine and will hold such engagement when the tool is withdrawn, thereby withdrawing the detached part from the well so that the boring may be continued in the same well.

40 In the accompanying drawings,

Figure 1 is a side elevation of my improved clamping tool in position in which it is about to be engaged with a section of tube or pipe.

45 Fig. 2 is a vertical sectional view illustrating the gripping devices engaging the tube or pipe.

Fig. 3 is a cross sectional view illustrating the positions of the gripping elements before they have effected rigid and firm engagement with the tube or pipe.

Fig. 4 is a similar view illustrating the gripping elements in firm engagement with the tube or pipe.

55 As illustrated the device includes a sleeve

1 which is flaring toward its lower end. The sleeve 1 is in connection with a frame comprising the two side arms 2 which are connected at their upper extremities with a ring or loop 3 with which the supporting 60 cable 4 may be connected.

The sleeve 1 is provided with a number of slots 5 each of which has an ear 6 on each side thereof. Cams in the form of eccentrically journaled disks 7 are supported in 65 the slots 5, the axial members 8 of said cam disks being journaled in bearings in the ears 6. The cam disks 7 have teeth or serrations on their peripheries as shown, so that when properly engaged with a tube or pipe a firm 70 and rigid grip will be effected in order to enable the gripping tool to retain its connection with the tube or pipe and withdraw the same from the well. Each of the cam disks has a projection 9, which projections 75 are arranged to engage or contact with the sleeve 1 above and below the ends of the slots 5 in which the cam disks operate. Thus each cam disk is permitted to turn about half of a revolution, the extent of turning 80 movement of the cam disks being limited by the projections 9.

In operation when any part of the boring mechanism in the well has become detached or broken from the operating mechanism, 85 the gripping tool being in connection with a sufficiently strong cable is lowered into the well until the upper end of the detached part of the boring mechanism is received or extended into the sleeve 1. As the sleeve is 90 lowered around the broken or detached part of the boring mechanism the teeth or serrations on the cam disks 7 contact therewith, but do not effect firm or rigid engagement with the detached part until the sleeve has 95 lowered a sufficient distance to receive the upper portion of said detached part. It can readily be ascertained whether the gripping tool has been lowered far enough, simply by pulling on the cable; because if the upper 100 portion of the broken or detached part is within the sleeve 1 any upward movement of said sleeve will cause the cam disks 7 to turn toward the positions illustrated in Fig. 2 and firmly grip the broken part as 105 shown. This gripping engagement is firmly positive and rigid so that by winding up the cable the detached or broken part of the boring mechanism will be withdrawn from the well after which the well may be bored 110

to a greater depth if desired, or finished without leaving therein the broken part of the boring machine.

A gripping tool of this construction is 5 very strong and may be economically manufactured. It entirely dispenses with the use of springs and similar objectionable actuating devices for effecting engagement with the broken part in the well. My invention 10 utilizes as the gripping elements the strong cam disks strongly supported so that when the gripping engagement is effected it is rigid and unyielding.

It will be apparent that the number of the 15 cam disks may be varied and that there may be various other modifications without departure from the principle and nature of the invention.

What I claim is:—

20 1. A clamping tool of the character described, comprising a sleeve arranged to encircle a detached part of a boring machine, and having slots near one end thereof, an eccentric cam disk supported in each of said 25 slots, and a projection on each of said cam disks arranged to engage against the sleeve at the lower end of the slot when the cam disk is in that position which it occupies when the portion thereof having the shorter 30 radius is toward the axis of the sleeve and arranged to engage against the sleeve above the slot to limit turning movement of the cam disk.

2. A clamping tool of the character described, comprising a sleeve arranged to encircle a detached part of a boring machine 35

and having slots near one end thereof, an eccentric cam disk supported for turning movement in each of said slots from a position in which the portion having the shorter 40 radius is toward the axis of the sleeve to a position in which the portion having a larger radius is toward the axis of the sleeve, and a projection on each of said cam disks arranged to engage against the sleeve at the 45 upper end of the slot to limit turning movement of the cam disk when the portion of the cam disk having the longer radius is toward the axis of the sleeve.

3. A clamping tool of the character described, comprising a sleeve arranged to encircle a detached part of a boring machine, and having slots near one end thereof, an eccentric cam disk supported in each of said 50 slots in such position that the portion having the shorter radius extends inwardly beyond the plane of the inner surface of the sleeve, a projection on each of said cam disks arranged to engage against the sleeve at the 55 lower end of the slot when the cam disk is 60 in that position which it occupies when the portion thereof having the shorter radius is toward the axis of the sleeve and arranged to engage against the sleeve above the slot to limit turning movement of the cam disk, and 65 serrations on the peripheries of the cam disks arranged to engage the detached part of the boring machine with pressure increasing according to the increase in power applied to the clamping tool and the resistance of the 70 detached part.

WILLIAM TRIPPE.
